UNITED STATES PATENT OFFICE.

NIKOLAUS SCHREDER AND STEFAN SCHREDER, OF CLEVELAND, OHIO.

COMBINED COAL AND GAS STOVE.

1,398,400.

Specification of Letters Patent. Patented Nov. 29, 1921.

Application filed October 17, 1919. Serial No. 331,337.

To all whom it may concern:

Be it known that we, NIKOLAUS SCHREDER and STEFAN SCHREDER, subjects of Hungary, residing at Cleveland, in the county of 5 Cuyahoga and State of Ohio, have invented certain new and useful Improvements in a Combined Coal and Gas Stove, of which the following is a specification.

This invention pertains to a combined gas 10 and coal stove in which either gas or coal alone can be burned, or both together, and which is so constructed that practically all the heat is given off into the room and a very small percentage escapes through the chimney flue, all substantially as shown and described and particularly pointed out in the 15 claims.

In the accompanying drawings, Figure 1 is a perspective view of the stove and Fig. 20 2 is a central sectional elevation front to rear. Fig. 3 is a transverse vertical section on a line corresponding to 3—3, Fig. 2. Fig. 4 is a plan view on a line corresponding to 4—4, Fig. 2.

25 Structurally the present stove is exclusively of cast metal, with a body *a* and base *b* on which the body of the stove is mounted. The said body contains two combustion chambers *c* and *d* respectively, of which the 30 front chamber *c* is exclusively a gas chamber having the gas burners 2 in its bottom and located at the front of the heater *b* and approximately half the height thereof. The chamber *c* is provided with an inwardly and 35 upwardly curved radiating top 3 and a removable front plate 4, which however, is fixed in place by a screw 5 through a stud 6 rigid with the base *b*, so that, when needed, this plate may be removed but otherwise 40 it remains permanently in place. The sides and rear of this chamber are of course permanent with the top 3. Air to support combustion enters through the perforated plate 8 at the bottom of chamber *c*, and draft proceeds from the top and rear of the chamber 45 through a box shaped draft space 10 having an externally controlled damper or lid 11 at its top adapted to be more or less opened for purposes of draft when the burners 2 are going, but which is closed when these burners are not used and there is fire only in chamber *d*. The gases of combustion rising from burners 2 escape through the said draft opening 10 and of course carry 50 a portion of heat with them, but this is mostly absorbed in the top of chamber *d*

and given off through the walls of said chamber. Furthermore, and to promote such absorption and radiation of heat into the room before it reaches the outlet flue 14, 60 we construct the front and top portion of chamber *d* with an inwardly stepped wall 15, which narrows the chamber step by step and exposes the large horizontal surfaces *f* of each step where the flow of the heat or hot 65 air is checked and absorbed, whether it comes across from chamber *c* or from fire in the bottom of chamber *d*.

Respecting the chamber *d* it will be seen that this chamber involves the dual fuel 70 principle, having a gas burner centrally in the bottom thereof and a grate and other features for burning coal or wood, and either hard fuel or gas may be used separately or both together, or the said burner may be 75 used in conjunction with the burners 2 in chamber *c*. Indeed, the construction is such that gas can be burned in chamber *c* simultaneously with coal or wood in chamber *b*, in which case the damper 11 is opened and 80 the draft controlled by damper 17 in the exhaust flue.

The chamber *d* has a suitable fire pot 18, fixed side grate bars 19 and middle rotatable grates on tube 20. The said grate tube 20 85 is confined to the fire pot and supported at its ends on the gas burner pipe 22, which extends through the said grate tube and the wall of the fire pot at both ends and is rotatably supported in the sides of the stove. 90 The said gas burner tube has a gas intake 21 at one end and a stem 23 at the other end provided with a crank handle 24 and one end of the grate tube 20 is fixed thereto by a screw, or its equivalent, so as to rotatably rock the grate tube through burner pipe 22 by means of the handle 24 when the grate is to be shaken to drop the ashes. Perforations 27 in the said burner tube or pipe 95 discharge the gas into the annular gas circulating belt or space about the same within outer tube 20, and these perforations are preferably along the top of pipe 22 so that the heat from above will strike through and heat the gas before it is ignited, and the gas 100 escapes from said belted area through perforations 29 in the sides and bottom of the tube 20, where it is ignited and burns up on both sides of said tube.

An ash pit 30 is provided beneath the coal 110 grate or burner provided with a drawer or pan 31 adapted not only to be used as an ash

receiving medium but serving also the function of a damper for air to the coal burner particularly, and whereby the draft for the coal fire is initially controlled. To this end 5 the said ash pit is open to the outer air at 32 in its rear, but an equivalent air intake could be provided, and the said ash pan or receptacle is of course pushed in when the grate is shaken to receive all the ashes and 10 more or less to control air to the fire.

All joints are sealed with rabbeted or overlapping edges to prevent possible escape of 15 gas into the room even if gas should accidentally escape from the burners without being lighted, as it would then be drawn up 20 the flue.

The steps *f* are found very convenient to 25 place pans or the like thereon to be heated or even for cooking. If coal or wood be used the gas burner 20—22 is employed to start the fire and is then turned off. The solid fuel is introduced through the door 35.

Importance is attached to the stepped 40 formation of the front and top of chamber *b* because the said steps are adapted to be utilized for heating vessels when either or 45 both chambers are being used, thus, in a working sense, making the steps a utility

portion of the front or gas chamber while in a mechanical or structural sense the steps 50 belong only to the rear chamber.

What we claim is:

1. In a combination stove as described, a heating chamber having fixed grate bars in its bottom and a rotatable grate member 35 therewith having a tubular body provided with perforation along its sides and bottom, and a gas supply tube extending through said tubular body having a line of perforations at its top and a crank therewith and 40 secured to said body to rock the same.

2. A combination stove for gas and solid fuel, comprising a chamber having fixed grate members in its bottom and sides for solid fuel and a middle tubular grate member 45 having perforations to emit gas, and a rotatable gas supply pipe on which said tubular grate member is fixedly mounted and provided with perforations to emit gas into said tubular member. 50

Signed at Cleveland, in the county of Cuyahoga, and State of Ohio, this 13th day of October, 1919.

NIKOLAUS SCHREDER.
STEFAN SCHREDER.
